PACKING RING

Charles V. Millikan, Tulsa, Okla., assignor to
Geophysical Research Corporation, New York,
N. Y., a corporation of New Jersey

Application July 4, 1945, Serial No. 603,127

6 Claims. (Cl. 166—10)

1

This invention relates to packing rings.

In the patent to Charles V. Millikan, No. 2,374,557, granted April 24, 1945, there is disclosed a procedure of separately testing the type of fluid being produced in each of several zones in a well and the rate at which the fluid is being produced. In the practice of this procedure, it is necessary to divide up a portion of the well into zones by a series of packing rings mounted tightly upon the exterior of the tubing through which the well is produced and with the outer circumference of each packing ring contacting the interior of the casing lining the well. The tubing must be lowered into the well with the packing rings attached and, therefore, the rim of the packing ring cannot be made to fit too tightly in the well casing because the abrasion necessarily occurring while the tubing is being lowered would severely damage the packing ring before it reaches its proper position in the well.

An object of this invention is a packing ring of such structure that it will pass through a long well casing while mounted on the tubing without suffering material damage and when it arrives at its proper position in the well casing will effectively co-operate therewith to form a fluid-tight seal.

Other objects, novel features and advantages of this invention will become apparent from the following specification and accompanying drawings, wherein:

Fig. 1 is a fragmentary section through a well containing a tubing and having mounted thereon packing rings embodying the invention;

Fig. 2 is a plan view of the packing ring shown in section in Fig. 1;

Fig. 3 is an enlarged section similar to Fig. 1, and

Fig. 4 is a fragmentary view of the inner surface of the packing ring substantially on the line 4—4 of Fig. 3.

In Fig. 1, 10 is a standard steel casing set into a bore hole in the ground with cement 11 in the usual manner. Within the casing 10 is a discharge tubing 12 which is provided at intervals with a number of packing rings 13, only two of which are herein illustrated, the packing rings contacting the inner surface of the casing 10 to form annular zones 14. While the spacing of the packing rings 13 may be varied, it has been found that a spacing of approximately three feet is satisfactory.

The casing 10 is provided with the usual apertures 15 communicating through passages 16 with the strata surrounding the well, these apertures

2

and the passageways being formed in the usual manner after the casing has been set in place by bullets shot from a special gun lowered into the casing. The discharge tubing 12 is provided with one or more apertures 17 between each pair of packing rings 13 to provide communication between each chamber 14 and the interior of the discharge tubing 12. Within the discharge tubing 12 is arranged the testing instrument 18 disclosed in detail in said Millikan Patent No. 2,374,557.

On the inner wall of the discharge tubing 12 are provided packing rings 19 which are spaced apart approximately the same distance as the packing rings 13 and are located closely adjacent 15 the same. Each pair of packing rings 19 forms an annular chamber 20 with the exterior of the instrument 18 when the instrument is so arranged that its exterior contacts both rings of the pair. The rings 19 are so designed that the instrument 20 18 fits them snugly but the instrument is capable of movement relative thereto so that it may be placed in and removed from the discharge tubing. When in proper position, the inlet 21 of the instrument 18 communicates with a single chamber 25 20 which in turn communicates with a single zone 14 so that only fluid from such zone is permitted to pass into the instrument 18.

The packing ring 13 is composed of suitable flexible and resilient material such, for example, 30 as oil-resistant rubber compound, rubber, etc. This ring comprises a sleeve 22 having an integral sealing flange 23. The flange 23 extends from the outer surface of the sleeve 22 midway the ends thereof outwardly and has a surface 24 35 contacting the inner surface of the casing 10. The flange 23 is sufficiently flexible that when a packing ring is being passed through the well casing, it bends easily to disengage the surface 24 from the inner surface of the casing 10 so that 40 damage to the sealing surface 24 is avoided.

The central portion of the inner surface of the sleeve 22 is hollowed out to form an annular recess 25. The ends of the surface of the sleeve constitute sealing surfaces 26 contacting the outer surface of the tubing 12. When the packing ring is mounted on the tubing, the recess 25 forms a chamber having a portion of the tubing forming its inner wall. A short distance above and below the recess 25, the inner surface of the packing ring 22 is cut circumferentially by slits 27 to form flexible lips or flaps 28. At each end of the sleeve 22, one or more passageways 29 lead from the exterior of the sleeve to the recess 25. The passageways 29 are normally closed at their inner 55 ends by the flaps 28 which form one-way valves.

The inner annular surfaces 30 of the flaps 28 are slightly relieved so that they do not make close contact with the tubing 12. When the pressure in a zone 14 is greater than the pressure in the chamber 25, fluid flow is directed from the exterior of the packing ring 22 to the chamber 25 by deflection of a flexible flap 28 as illustrated in Fig. 3 (bottom flap) or Fig. 4. The remaining flap 28 remains in its normally closed position as shown in Fig. 3 (top flap). For ease of illustration, the passageways 29 have been shown in the same vertical radial plane whereas actually no two of the passageways are necessarily in the same vertical radial plane.

Assume that the packing ring 13 is in the position shown in the well casing with the surface 24 of the flange 23 engaging the inner surface of the casing 10 and that equal pressure exists above and below said flange. The same pressure exists in the chamber 25 and both sets of passageways 29 are obstructed at their inner ends by the flaps 28 being closed. Under these circumstances, there will be no tendency for the fluid to flow between the surface 24 and the inner surface of the casing 10.

In the event that the pressure on one side of the packing ring flange 23 exceeds the pressure on the other side thereof, fluid will tend to flow between the surface 24 and the inner surface of the well casing from the side of higher pressure to the side of lower pressure. However, the increased pressure on one side of the flange 23 is also applied to the flaps 28 at the inner ends of the passageways 29 communicating with the higher pressure side to deflect said flaps and as shown in Fig. 4, thus permit the higher pressure to be applied through the open slits 27 over the entire inner wall of the chamber 25. The remaining flaps 28 prevent fluid flow through the chamber 25 and remaining passageways 29 to the lower pressure side. The force thus exerted on the chamber wall urges it outwardly and engages the surface 24 of the sealing flange 23 tightly against the surface of the casing 10. The increased pressure in the chamber 25 also tends to produce leakage from the chamber 25 between the surface of the tubing 12 and the sealing surface 26 on the lower pressure side. Such leakage is very small because the packing ring 13 is made to fit very snugly on the tubing 12 and is insufficient to interfere with the above-described operation. The small amount of leakage which does occur is desirable since it permits the pressure in the chamber 25 to bleed off as the packing ring 13 is being removed from the casing and thereby avoids damage to the flange 23 during removal. A very small pressure increase applied to the interior of the chamber 25 produces a very large outward force against the sealing flange 23 by reason of the large area over which the pressure is applied.

It is of course understood that various changes may be made in the structure above described without in any way departing from the spirit of the invention as defined in the appended claims, for example, the one-way valves at the ends of the passageways 29 may be differently made than as specifically disclosed, the flap arrangement merely being an example of a convenient form of valve.

I claim:

1. A packing ring comprising a flexible resilient sleeve having an integral flexible resilient peripheral flange, an annular recess in the inner surface of said sleeve, passageways leading to said recess from the exterior surface of said sleeve at

either side of said flange, and means for preventing fluid flow from said recess through said passageways while permitting flow in the reverse direction.

5 2. A packing ring for use between a well tubing and a well casing, said ring comprising a flexible resilient sleeve adapted snugly to surround the tubing and having an integral flexible resilient peripheral flange adapted to contact the casing, 10 an annular recess in the inner surface of said sleeve constituting a chamber having a section of the well tubing surface forming a portion of its wall, passageways leading to said recess through the sleeve from the exterior thereof at either side of said flange, and means for preventing flow from said chamber through either passageway while permitting flow in the reverse direction.

15 3. A packing ring comprising a flexible resilient sleeve having an integral flexible resilient flange, a recess in the inner surface of said sleeve, a passageway leading toward said recess from the exterior surface of said sleeve at either side of said flange, and a slit in said sleeve leading from 20 the inner end of each passageway to said recess, said slit permitting flow through said passageway into said recess but preventing flow from said recess into said passageway.

25 4. A packing ring for use between a well tubing and a well casing, said ring comprising a flexible resilient sleeve adapted snugly to surround the tubing and having an integral flexible resilient peripheral flange adapted to contact the casing, a recess in the inner surface of said sleeve constituting a chamber having a section of the well tubing surface forming a portion of its wall, a passageway leading toward said chamber from the exterior of said sleeve at either side of said flange, and a slit in said sleeve leading from 30 the inner end of each passageway to said recess, said slit permitting flow from said passageway into said chamber but preventing flow from said chamber into said passageway.

35 5. A packing ring comprising a flexible resilient sleeve having an integral, flexible, resilient peripheral flange, and an annular recess in the inner surface of said sleeve, said sleeve having provision for admitting fluid from the exterior of said sleeve at either side of said flange into said recess while preventing flow in the reverse direction.

40 6. A packing ring for use in the annular space between two concentric different-diameter tubes, said ring comprising a flexible resilient sleeve 45 adapted snugly to surround the inner tube and having an integral, flexible, resilient peripheral flange adapted to contact the outer tube, and an annular recess in the inner surface of said sleeve constituting a chamber having a section of the inner tube surface forming a portion of its wall, said sleeve having provision for admitting fluid 50 into said chamber from either side of said flange while preventing flow out of said chamber.
